UNITED STATES PATENT OFFICE.

FRANCIS E. MERRIMAN, OF BOSTON, MASSACHUSETTS, ASSIGNOR TO
HERBERT N. KINGSBURY, OF WESTFIELD, MASSACHUSETTS.

CUTTING-TOOL.

SPECIFICATION forming part of Letters Patent No. 605,582, dated June 14, 1898.

Application filed October 29, 1897. Serial No. 656,780. (No model.)

To all whom it may concern:

Be it known that I, FRANCIS E. MERRIMAN, a citizen of the United States, residing at Boston, in the county of Suffolk and State of Massachusetts, have invented certain new and useful Improvements in Cutting-Tools, of which the following is a specification, reference being had thereto in the accompanying drawings.

This invention relates to that class of hand tools or implements adapted especially for cutting leather and other flexible material into strips of predetermined thickness and wherein in a uniform thickness may be maintained or the strips may be made thicker at one or more portions and then tapered or made thinner at other portions, the said variation in the thickness of the cut occurring simultaneously with the passage of the tool or implement across the piece being operated upon.

My invention consists of the parts and the constructions and combinations of parts forming the improved tool, which I will hereinafter describe and claim.

The object of the invention is to devise a hand tool or cutting implement which by means of the devices hereinafter set forth operates upon a knife or cutting-blade so that while the tool may be made to cut a strip of leather or other material of uniform thickness from end to end it can also be manipulated so that it will cut the strip with a continuous taper or with gradually increasing and decreasing thicknesses; these changes in the method of cutting taking place during the cutting operation and being within the control of the operator. By this means I am enabled to produce a strip or article for leather-working purposes which shall be thin in one (or more) part and thick in another or of equal thickness throughout and without waste of leather or material.

In carrying out my invention I use a tool or implement of the type shown in the accompanying drawings, wherein—

Figure 1 represents a front view of the improved tool. Fig. 2 is a top plan view of the same, and Fig. 3 is a bottom plan. Fig. 4 is a longitudinal sectional view on the line 2 2 of Fig. 2. Fig. 5 is a cross-sectional view on the line 3 3 of Fig. 3. Fig. 6 is a detail of the plate I.

The stock or body A of the tool is preferably of square or rectangular form in cross-section. It is best made of metal and has projecting from its ends the handles B, which are grasped to draw the tool over the material to be cut. Transversely through the stock or body and opening out through the front and rear sides and bottom of the same is an opening C, in which a block or gage D is slidably mounted, said block or gage carrying a pointer E or means whereby the adjustment of the block or gage from the knife or cutting-blade may be read and accurately determined in connection with a scale or series of graduations on a plate F, fitted to the front of the stock with its edge proximate to the pointer on the slideable block or gage, as shown in Fig. 1.

The knife or cutting-blade G may be of any appropriate and well-known form. It is herein shown as having its cutting edge curved, and it is securely and rigidly clamped against the bottom of the stock or body by the means I will now disclose.

Two clamping-plates H are employed to hold the knife or cutting-blade, each of said plates engaging and clamping the end portions of the knife, which lie outside of the vertical plane of the walls of the opening C, whereby the central or cutting portion of the knife is unobstructed. Each of the clamping-plates H is provided with two holes a b, one formed in it just outside of the adjacent end of the knife and the other in the outer portion. The holes a receive the screws c, which pass loosely through them and enter threaded holes d in the bottom of the stock or body, while the holes b are threaded and receive screws e, having smooth or unthreaded points or ends adapted to enter and form fulcrums in corresponding cavities f in the bottom of the stock or body. By reason of this construction it will be apparent that when the knife or cutting-blade is inserted beneath the clamping-plates H and the screws c turned down the said knife or blade will be held, but possibly not with sufficient pressure to resist hard work. To insure the fixidity of the knife or cutter, I prefer to use the fulcrum-screws e, and when the screws c have been seated, as just described, the other screws

e are turned down, their conical or rounded points turning in the cavities and their threaded portions working in the threaded holes b in the plates II, which results in the outer ends or heels of the plates being slightly lifted. This forces the toes or clamping ends of the plates II down hard on the ends of the knife or blade and secures said blade against movement during the cutting operation.

10 This arrangement of the screws e has been found by experiment to be far superior to the employment of two screws for each plate, each of said screws screwing directly into the stock or body, as described for the screws c.

15 On the top of the stock or body is secured a plate I, the surface of which is provided with radial lines g; but, if desired, the said plate I may be omitted and the lines made directly in or on the top surface of the body or stock. The arrangement and numbering of the lines may be varied as suits the convenience or desire of the operator, but they are herein shown as radiating from the vertical center of the stock and bearing the 20 groups of numbers "8" to "12," "9" to "13," "10" to "14," and "11" to "15," to be read in connection with a pointer and the scale on the front of the stock, as I will now describe.

The adjustable block or gage D has two upwardly-projecting guide pins or studs D', which pass through the top of the stock or body and receive at their outer ends a transverse plate or follower J, having a central opening h. In the center of the stock is also made a hole l, in which is threaded a left-hand screw K, whose lower end bears against the block or gage D, while a shoulder at m bears under the cross-plate or follower J, the said screw having a reduced extension, to 35 which is securely fitted a disk or thumb-wheel or finger-piece M, provided with a pointer N. If desired, a lever may be substituted for the disk, as shown by dotted lines, Fig. 2, without departing from the spirit of my invention. The pointer N operates over and is read with the numbered lines on the top of the stock.

40 The device being thus detailed its operation will be substantially as follows: Assuming that the plate on the front of the stock is graduated into thirty-second parts of an inch and that the block or gage D has been adjusted until its pointer registers with the graduation indicating eight thirty-seconds on 45 the plate I, the pointer N on the disk or finger-wheel M or the lever, if used, will be found to register with the mark or line on top of the stock or body which carries the numeral "8." In this position of the parts the bottom of the block or gage D will be removed eight thirty-seconds of an inch from the cutting edge of the knife, and the tool will cut a uniform strip of this thickness as long as this adjustment remains. If the disk or wheel 55 M is turned to bring its pointer over any of the succeeding lines on the top of the stock, the screw K operates under the plate or fol-

lower J, and thereby raises the block or gage D a distance corresponding with the numeral over which the pointer N is stopped. Thus 70 if the pointer N is turned to the line marked "10" the block or gage D will be raised to a point which causes its pointer to register with a graduation on the plate corresponding with ten thirty-seconds of an inch, and the strip 75 now cut from the material will be of that thickness. By reading the pointer N with the numbered lines on the stock or body the operator can always tell the "set" or adjustment of the gage or block with reference to 80 the cutter and the thickness of the strip to be cut.

85 As the block or gage D is freely moved up and down by the simple turning of the disk or finger-wheel, (or lever,) it is apparent that if it is desired to cut a strip with a gradual taper from end to end the operator simply continuously turns the disk or wheel during the cutting process, which results in a gradual and continuous alteration of the space between the block D and knife or cutter, and if the operator desires to cut a strip with alternate thick and thin portions the wheel or disk is moved right and left to effect the purpose.

90 The wheel or disk is readily moved by the fingers, and in the hands of a skilled operator may be manipulated without difficulty, and by simply registering the pointer on the disk with the lines on the top of the stock he may 100 accurately cut the regular or irregular strips as he desires without referring to the gage D and without any interruption in the continuous cutting operation or stroke.

95 Having thus described my invention, what I claim as new, and desire to secure by Letters Patent, is—

1. In a cutting tool or implement, the stock or body having an opening made transversely through it, in combination with a block or gage adjustable in said opening, a knife or cutter beneath the block or gage, a screw, threaded in the stock or body and engaging the block or gage, and a plate or follower connected to and movable with the block or gage 110 and engaged by the screw whereby the block or gage is adjusted with relation to the knife or cutter, and means for indicating the extent of said adjustment.

115 2. In a cutting tool or implement, the combination of the stock or body, a knife or cutter fitted thereto, a block or gage movable within the stock or body toward and from the knife or cutter, and means whereby the block or gage may be continuously moved during 120 the cutting operation, consisting of a screw, threaded in the stock or body and engaging said block and a finger-piece for operating the screw.

125 3. The stock or body having a transverse opening, a block or gage adjustable in said opening and provided with upwardly-extending studs or guide-pins, a plate or follower fitted to the upper ends of the studs or pins

exterior of the stock or body, a screw passing through a threaded opening in the stock or body and engaging said block or gage, for adjusting the latter, a knife or cutter beneath 5 the block or gage and means for indicating the extent of movement of the block or gage.

4. The stock or body having the vertically-adjustable block or gage, a scale or series of graduations proximate to the block or gage, a 10 screw and connections for adjusting the block or gage, a knife or cutter and means for securing it in place and means for determining the adjustment of the block or gage with reference to the knife or cutter, consisting of 15 radial lines on the top of the stock and a pointer movable with the screw and adapted to be alined with said lines.

5. A leather-cutting tool or implement comprising a handled stock or body having a transverse central recess and threaded top opening, a block or gage adjustable in said recess 20 and provided with guide-pins or studs, ex-

tending through the top of the stock, a plate or follower connecting said pins or studs and having a central opening, a screw working in the threaded opening of the stock and passing loosely through the opening in the follower, and having a shoulder bearing under the latter, whereby the block is raised and lowered, a knife or cutter and means for securing it in 25 position below the block or gage, a scale or series of graduations on the stock proximate to the block or gage, a plate on the top of the stock, having radial lines, and a finger-piece on the screw having a pointer to be moved 30 over the radial lines, for indicating the relation of the block to the cutter.

In testimony whereof I affix my signature in presence of two witnesses.

FRANCIS E. MERRIMAN.
